UNITED STATES PATENT OFFICE.

MEYER BALLIN, OF CHICAGO, ILLINOIS.

DESIGN FOR A BROOCH.

SPECIFICATION forming part of Design No. 18,929, dated February 19, 1889.

Application filed June 28, 1888. Serial No. 278,472. Term of patent 14 years.

To all whom it may concern:

Be it known that I, MEYER BALLIN, a citizen of the United States, residing at Chicago, in the county of Cook and State of Illinois, have invented and produced a new and original Design for Jewelry, which is fully set forth in the following specification, reference being had to the accompanying drawing, forming a part thereof, in which the figure shows a plan 10 of my design applied to a brooch or other like piece of jewelry.

The main features of my design are a dog sitting upon his haunches and a little child sitting in front of the dog and holding a dish 15 in its partially-extended arms.

In the figure of the drawing, A represents a brooch or other like article of jewelry. It is 20 to the surface ornamentation of this article that my design relates. The brooch A is surrounded by a suitable ornamental border, a, and has upon its face the representation of a

base, B, above which and represented as resting upon said base is a dog, C, arranged at one end of the base in the position shown, sitting upon his haunches, while at the other 25 end is a child, D, holding in its arms extended toward the dog a dish, E.

Having thus described my invention, what I claim as new, and desire to secure by Letters Patent, is—

The design for jewelry hereinbefore shown and described, the same consisting of the brooch or other article of jewelry, A, having the surface ornamentation set forth, to wit: the representation of a sitting dog and a child 35 sitting in front thereof and holding a dish, all arranged upon a suitable base, substantially as set forth.

MEYER BALLIN.
